UNITED STATES PATENT OFFICE.

HARRY TUNSTALL, OF FAIRHAVEN, MASSACHUSETTS, ASSIGNOR TO ALSATIAN MACHINE WORKS, LIMITED, OF BOSTON, MASSACHUSETTS, A CORPORATION OF MASSACHUSETTS.

WASTE-DELIVERY MEANS.

Application filed November 14, 1923. Serial No. 674,710.

To all whom it may concern:

Be it known that I, HARRY TUNSTALL, a subject of George V, King of England, and a resident of Fairhaven, in the county of 5 Bristol and State of Massachusetts, have invented a new and useful Improvement in Waste-Delivery Means, of which the following is a specification.

In Letters Patent issued to me No. 1,351,- 10 076, dated August 31, 1920, there is shown a combing machine in which the waste is removed from the cylindrical combs by means of rotary brushes and is delivered upon a cylinder running the length of the 15 machine to which it is drawn by suction in the usual way. I have found that while this arrangement is in many respects satisfactory, in a machine where there are a number of heads, each containing in itself a complete combing mechanism so that the amount of waste is considerable, especially where the mechanisms of these said heads are arranged back to back as in my said patent, a better result can be secured by the means herein- 20 25 after described. In my description I have shown only so much of a twelve-headed comber of the character described in my said patent as is necessary to explain my invention, and so far as the parts shown are similar to those in my said patent I have given 30 to them their corresponding reference characters.

My invention is shown in the drawings in its preferred form.

Figures 1 and 1^a show partly in side elevation and partly in section mechanism embodying my invention, it being understood that Fig. 1^a is an extension to the left of the mechanism shown in Fig. 1.

Figs. 2 and 2^a are plan views similarly arranged of my delivery mechanism, portions thereof being in section.

Fig. 3 is a view partly in cross section showing one of the end plates of the box viewed from the outside;

Fig. 4 a section on line 4—4 of Fig. 2, and

Figs. 5 and 6 are views of the two ends of so much of my said combing machine as relates to my present improvement, together with the means for operating my improvement.

64 is one of the boxes within which the cylindrical combs and their brushes are located. One box is provided for each pair

of heads. This resembles the box 64 in my 55 said patent except that its ends are made in three sections, a central section 14 to which is attached as at 18 two side sections 15 and 16 and the outer walls 15 and 16 of this box carry inner walls 641 to conform somewhat in shape to the outer surfaces of the cylindrical combs and so reduce the capacity and improve the utility of the box. The cylindrical combs 62 are mounted on shafts 63 which may be operated in any convenient 60 way, for example, as shown in my said patent or preferably in the way shown in a companion application hereto Serial No. 674,708. So also the brushes 66 are mounted on shafts 67 and are rotated in opposite directions toward each other as in said patent to receive and carry down the waste. The waste brushed from the cylindrical combs is thrown by the brushes down toward the bottom of the box 64 and is drawn by suc- 70 75 tion against and between rotary drums 129 rotating in opposite directions and between which it is drawn out of the box.

I preferably use two drums between which the waste *a* is drawn. Each drum comprises 80 an outer cylinder 1 which is perforated around its circumference within the casing and within it is an imperforate cylinder 2 in which, however, there are openings 3, 4, 5, 6, 7 and 8, one opening for each pair 85 of heads. Preferably some of these openings are in one cylinder and some in the other cylinder for the better utilization of the suction. As shown, openings 3, 4 and 5 are in one cylinder and openings 6, 7 and 8 in 90 the other cylinder. These openings are of substantially the length of the heads. At one end of the drums is located a fan 139 which may be of any desired construction and hence is not shown in detail. The purpose of this fan is to create a suction in the drums which will cause the waste to be drawn between the cylinders 1 which as they rotate toward each other will compress the waste and feed it out from the box, and also 100 to withdraw any dust and lint which may fall into the interior cylinder 2 through the openings 3, etc. The fan 139 is connected to both cylinders 2 by a funnel-shaped connection 139^a large enough at one end to receive the ends of the two cylinders 2 and at the other end small enough to enter the fan casing 139.

The outer member or cylinder 1 of each drum 129 is caused to rotate intermittently by means of intermeshing gears 9 and 10, each attached to one end of a cylinder 1, which are suitably mounted in bearings on a support 11 to rotate therein. A pinion 132 mounted on shaft 133 in a hanger A¹ from the frame A engages the gear 10 and is operated intermittently by means of a ratchet 134 also on shaft 133 and pawl 135. This pawl is mounted on a lever 12 also fulcrumed on the shaft 133 and operated by means of the link 137 connected to a rocker arm 13 hung on the rock shaft 103. By this means as the arm 13 is rocked it moves the pawl 135 to give a step-by-step motion to the ratchet 134 which turning the pinion 132 rotates the gear 10 which in turn rotates the gear 9, thus turning the cylinders 1 of the drums.

There are two rock shafts 103 shown herein and in my said patent, both supported in brackets 104. Both rock shafts are operated by links from a crank disk 105 on shaft 8. As shown in Fig. 6, however, I use but one link 107 and connect both rocker arms 108, carried by the rock shafts 103, by a link 108^a.

As suggested above, I preferably equalize the suction between the front and rear ends of the drums by dividing the openings 3, 4, etc., which connect the interior of the drums with the interior of the boxes, between the two stationary cylinders 2 as shown, and I also graduate the size of said openings, those near the fan being smaller than those farther away from the fan. This is indicated in the drawings where the openings which in each case are approximately the length of a head, vary in width so as to render effective an increasing number of perforations in the cylinder 1 as air passages from the interior of its box to the interior of the cylinder 2. Small openings 641^a in the top 641 of the box provide air inlets through which air will pass into the box.

Each box covers the cylindrical combs for one pair of heads and the ends of each box are preferably made as shown in three parts, a central part 14 and two side parts 15 and 16, these several parts being bolted together or otherwise attached as at 18, the whole being mounted upon the frame A.

The fan 139 has a delivery opening 139^a through which the dust and lint withdrawn from the interior of the imperforate cylinders 2 is blown off.

While the construction is desirable for six double heads, i. e. twelve heads back to back as in my said patent, each having a nipper frame and a top comb, the number and size of the openings may be varied according to circumstances, and my drums 65 may be further modified in like manner for

a machine of the usual construction having single heads.

It is of course understood that the details of my machine may be varied without departing from my invention. The above construction I have found practical in every way and useful in a double combor of the kind described.

It will be noted that the openings 66^a for the brushes in the box ends are oval. This allows for a slight vertical adjustment for the brushes as they get worn. In practice the brushes are long enough to fill closely the space between the ends of the casing so as to reduce to a minimum the income of air 80 through the openings 66^a into the boxes.

What I claim as my invention is:—

1. A waste-delivery mechanism comprising a suction fan, a pair of drums located side by side connected to said fan, each drum comprising an outer perforated rotatable member and a substantially closed inner stationary member, means for rotating said outer members toward each other, and openings in said inner members spaced apart and located to provide air passages through each drum at points contiguous to the other drum.

2. In a machine of the kind described, a casing having an opening at the bottom, two drums located to close said opening, said drums each having an outer perforated rotatable member and means for rotating said outer members toward each other whereby waste from said casing and engaging said members will be withdrawn from said casing, stationary substantially closed inner members provided with openings, and suction means adapted to cause a suction from the interior of said casing through said openings and perforations and draw the contents of said casing to said drums.

3. In a fibre waste-delivery mechanism comprising a casing, two drums each comprising an outer perforated rotary member and an inner stationary member provided with openings at points along its length, said drums being located side by side at the bottom of said casing and in close proximity to each other, a suction means located at one end of said drums and adapted to withdraw air from said casing, said openings being graduated in size whereby the suction at the several openings along said drums will be substantially equally distributed.

4. In a combing machine a fan, a pair of drums located side by side, each drum comprising an outer perforated rotatable member and an inner cylindrical stationary member having openings located to cooperate with said fan in providing suction through said drums and means for rotating said outer members towards each other.
